5 Claims

ABSTRACT OF THE DISCLOSURE

Carburetor icing of internal combustion engines using volatile hydrocarbon fuels is prevented by treating such fuels with a phosphorylated imidazoline composition.

This application is a continuation-in-part of my earlier filed co-pending application, Ser. No. 509,189, filed Nov. 22, 1965, now abandoned.

BACKGROUND OF THE INVENTION

The problem of carburetor throttle blade icing and its attendant effect on the operation of internal combustion engines is well known. Poor engine performance in cold weather, as evidenced by stalling and bucking, is an experience shared by many motorists who operate automobiles in many areas where intemperate weather conditions prevail during the winter months.

Five conditions are usually necessary to promote carburetor icing: (1) critical engine type, (2) low engine load, (3) air temperature from approximately 35° to 45° F., (4) 100% humidity and (5) volatile winter-grade gasoline, that is, a gasoline having a Reid Vapor Pressure of at least 10 lbs./sq. in. at 100° F. (A.S.T.M. Method Designation D-323) and/or having a distillation curve such that at least 50% by volume of said gasoline distills over 212° F. When these circumstances concur, ice usually forms on the throttle blade and in the 40 throttle blade opening, which in turn causes malfunctioning of the carburetor.

Improved carburetor design has not substantially alleviated this problem. One method of overcoming the difficulty is to add chemical de-icers to the fuel. In most instances, these chemicals are composed of lower monohydric alcohols when used at dosages of 1%—2% or more, based on the weight of the fuel. Such large dosages could naturally dilute the fuel, unless care is used in their addition. For this reason, it has become popular to add the de-icer at the refinery level rather than to have service station operators make the addition directly to the fuel tank. It would be a valuable contribution to the art if a de-icing chemical were available which would be effective by adding very small amounts to fuels used in internal combustion engines.

SUMMARY OF THE INVENTION

In accordance with the invention, it has been found that carburetor icing may be avoided by adding to a volatile hydro-carbon liquid fuel burned in internal combustion engines a de-icing amount of the compositions of this invention.

The de-icing composition consists of an equimolar phosphorylated composition having the formulae:

where E is from the group consisting of:

2

(A) a 1-alkanol or alkylamine 2-substituted imidazoline radical, and

(B) a monohydric alcohol or an aliphatic primary amine having 1—18 carbon atoms

5 with the proviso that at least 3 occurrences of E are (A).

In a preferred embodiment, E is entirely the 1-alkanol-2-substituted imidazoline radical.

Since the compositions contain free acid and amine groups, a certain amount of salt formation occurs when the compositions are in the form of a solution.

It has also been found that the phosphorylated composition of this invention may be used as a gasoline detergent.

OBJECTS

It is an object of this invention to provide a new chemical process for preventing the icing of carburetors.

Another object is to prevent carburetor icing by adding to the fuel small, yet effective, amounts of a chemical de-icer.

Other objects will appear hereinafter.

INVENTION

The first starting material to produce the de-icing composition is a phosphorous compound calculated as P_4O_{10} . A wide variety of phosphorous containing acidic compounds may be used, such as phosphoric acid, phosphorous oxychloride, phosphorous anhydride, etc. Most preferred for the purposes of this invention is phosphorous pentoxide.

The second component which is used to form the de-icing composition of this invention is a 1-alkanol, or alkylamino 2-substituted imidazoline which is defined by the following formula:

where R is an aliphatic group of 1—22 carbon atoms in chain length, Y and Z are selected from the group consisting of hydrogen and lower aliphatic hydrocarbon groups of not more than 6 carbon atoms in chain length, R_1 is an alkylene radical of 1—6 carbon atoms, Q is either O or NH, and n is an integer of 1—50.

When Q is O, the corresponding alkanol imidazolines may be formed generally by the reaction of alkanol amines such as aminoethyl ethanolamine and the like, with a fatty acid under conditions which effect ring closure. Broadly defined, the fatty acids which are useful in the invention are those fatty acids having from 12 to 24 carbon atoms, which are liquid at room temperature. Specific examples of fatty acids which may be used are myristoleic acid, palmitoleic acid, oleic acid, linoleic acid, linolenic acid and ricinolenic acid. Also useful as fatty acids in this invention are many of the mixed fatty acids, such as distilled coconut fatty acid, red oil fatty acid, vegetable fatty acids such as distilled cotton-seed fatty acid, distilled soybean and fractionated soybean fatty acid, tall oil fatty acid, distilled linseed fatty acid and the like. The mixed fatty acids are lower in cost and therefore constitute a preferred species for use in this invention. Also preferred is oleic acid.

Two typical alkanol imidazolines which may be used in the process of this invention are 1-(2-hydroxyethyl)-2-coco imidazoline and 1-(2-hydroxyethyl)-2-tall oil imidazoline, both of which compounds are conveniently pre-

pared using the teachings of Wilson U.S. 2,267,965. Other types of typical imidazolines which may be used are:

- (1) 1-(2-hydroxyethyl)-2-undecyl imidazoline;
- (2) 1-(2-hydroxyethyl)-2-tridecyl imidazoline;
- (3) 1-(2-hydroxyethyl)-2-pentadecyl imidazoline;
- (4) 1-(2-hydroxyethyl)-2-heptadecyl imidazoline.

Imidazolines having the above formula, where the substituted groups are those radicals having between 12 and 22 carbon atoms, either substituted or unsubstituted, are particularly suitable. Especially preferred radicals are heptadecenyl, heptadecadienyl, heptadecyl and pentadecyl radicals and mixtures thereof.

When Q is NH, the corresponding imidazolines may be formed generally by the reaction of an amine such as diethylenetriamine and the like with a fatty acid under conditions which effect ring closure. Broadly defined, the fatty acids with which the amine may be reacted are those having from 12 to 24 carbon atoms, which are liquid at room temperature. Specific examples of such fatty acids are the same as those listed above.

Two typical alkylamino imidazolines which may be used in the process of this invention are 1-(2-aminoethyl)-2-coco imidazoline and 1-(2-aminoethyl)-2-tall oil imidazoline. Other types of typical imidazolines which may be used are:

- (1) 1-(2-aminoethyl)-2-undecyl imidazoline;
- (2) 1-(2-aminoethyl)-2-tridecyl imidazoline;
- (3) 1-(2-aminoethyl)-2-pentadecyl imidazoline;
- (4) 1-(2-aminoethyl)-2-heptadecyl imidazoline.

Alkylamino imidazolines having the above formula, where the substituted groups are those radicals having between 12 and 22 carbon atoms, either substituted or unsubstituted, are particularly suitable. Especially preferred radicals are heptadecenyl, heptadecadienyl, heptadecyl and pentadecyl radicals and mixtures thereof.

The reaction between P_4O_{10} and 1-alkanol or alkylamino 2-substituted imidazoline takes place at a temperature of about 130-180° C. for 1-3 hours. It yields in equi-molar proportions the following products:

and

The identification of R, R₁, Q, Y, and Z has been given above.

When the reactant composition includes a monohydric alcohol then 6 moles of imidazoline per mole of P_4O_{10} are not required.

It has been found to be absolutely essential that the mole ratio of A:B, as described above, range from no less than 1:3 to 1:6 since at least 3 moles of imidazoline per mole of P_4O_{10} are necessary to impart de-icing activity to the resulting de-icing composition. When less than 6 moles of imidazoline are used, it is also essential to provide a third compound which will react at a temperature of 120-180° C. for a period of 3-4 hours with the remaining bonds in the P_4O_{10} molecule.

Monohydric alcohols have been found to be surprisingly effective as a third reactant. The amount of alcohol required to form the compounds of this invention may be therefore defined as being that amount sufficient to provide a mole ratio of starting reactants of A:B+C equal to 1:6 when C represents the moles of monohydric alcohol

present. Thus, if, for example, 3 moles of the imidazoline are employed, an additional 3 moles of alcohol will be necessary. If 6 moles of imidazoline are employed per mole of P_4O_{10} , no alcohol will be necessary to satisfy the requirements set forth above.

If less than 6 but 3 or more moles of imidazoline per mole of P_4O_{10} are used, a monohydric alcohol is added to the reactant system such that the total moles of imidazoline and monohydric alcohol are 6 per mole of P_4O_{10} used.

The referred to alcoholic reactants may be chosen from a wide variety of monohydric alcohols.

The classes of alcohols which are suitable for use are:

- (1) Aliphatic alcohols
- (2) Alicyclic alcohols
- (3) Ethylenically unsaturated alcohols
- (4) Acetylenically unsaturated alcohols
- (5) Araliphatic alcohols
- (6) Aromatic-ethylenically unsaturated alcohols
- (7) Oxo alcohols

Primary and secondary alcohols are greatly preferred.

Examples of the aliphatic alcohol reactants are ethyl, n-propyl, n-butyl, n-amyl, n-hexyl, n-heptyl, n-octyl, n-nonyl, n-decyl, n-undecyl, n-dodecyl (lauryl), n-tetradecyl (myristyl), n-hexadecyl (cetyl), and n-octadecyl (stearyl); branched chain primary alcohols such as isobutyl, isoamyl, 2-2,4-trimethyl-1-octanol and secondary alcohols such as isopropyl, sec-butyl, 2-pentanol, 2-octanol, 4-methyl-2-pentanol, and 2,4-dimethyl-3-pentanol.

The alicyclic alcohols may be illustrated by cyclopentanol cyclohexanol, cycloheptanol and methanol.

Examples of ethylenically unsaturated alcohols are allyl, crotyl, oleyl, (cis-9-octadecen-10-ol), citronellol and geraniol.

Acetylenically unsaturated alcohols are illustrated by propargyl alcohol.

Araliphatic alcohols are illustrated by benzyl, 2-phenyl-ethanol, hydrocinnamyl, and alpha-methyl-benzyl alcohols.

The aromatic-ethylenically unsaturated alcohols are illustrated by cinnamyl, where the replaceable hydrogen is on the alkyl group.

Oxo alcohols are normally a mixture of various intermediate molecular weight alcohols ranging from 4 to about 16 carbon atoms. Their preparation and description is described in the book "Higher Oxo Alcohols" by L. F. Hatch, Enjay Company, Inc., 1957, which disclosure is hereby incorporated by reference. The general range of both alcohols and ester by-products typifying an oxo alcohol still bottom of the type which may be used in the invention, is as follows:

Ingredient:	Percent
Mixed iso- and n-octyl alcohol	2-20
Mixed iso- and n-nonyl alcohol	5-40
Mixed iso- and n-decyl and higher alcohols	25-90
Esters	20-80

A typical oxo alcohol still bottom which finds excellent use in preparing the compounds of the invention has the following composition.

Ingredient:	Percent
C_8 alcohols	5
C_9 alcohols	10
C_{10} and higher alcohols	35
Esters	45
Soaps	5

Aliphatic primary amines may be substituted for the monohydric alcohol. The aliphatic group of such aliphatic primary amines contains 12-22 carbon atoms in their chain length. Specific examples of aliphatic primary amines which may be used are n-dodecyl amine, n-tetradecyl amine, dicoco amine, n-hexadecyl amine, n-octadecyl amine, and the like.

The formation of the de-icing composition of this in-

vention is best accomplished by first reacting the phosphorous compound with the imidazoline. It is essential for the purposes of this invention that at least 3 moles of the imidazoline per mole of the phosphorous compound, calculated as P_4O_{10} , be employed. Excellent compounds which show surprising ability as de-icing additives have been prepared where the ratio of imidazoline to phosphorous compound ranges from 3:1 to 6:1.

To illustrate the preparation of a de-icing compound of this invention, the following is presented. One gram mole of phosphorous pentoxide, calculated as P_4O_{10} , was added to kerosene to form a slurry. To this slurry, 4 gram moles of 1 - (2-hydroxy-ethyl)-2-heptadecenyl-2-imidazoline was slowly added with agitation. This mixture was then heated to about 130° C. for 1½ hours. At this point, the imidazoline had completely reacted with the phosphorous compound. Then, two moles of oxo alcohol were added and the mixture was heated at a temperature ranging from 100° to 120° C. for 3 hours. The resulting solution was red-orange in color, was clear and had a concentration of approximately 25%. Later testing of this composition showed excellent de-icing properties.

While compositions as described above may be used as produced, it may be desirable to dissolve them into a hydrocarbon liquid carrier, which makes proportioning of the treatment into the hydrocarbon fuel a simple matter. Such solvents as benzene, xylene, toluene, heptane and the like are suitable for this purpose. Also, the well-known blends of fractionated aromatic petroleum based products are economical choices as solvents.

The amount of the de-icing composition which may be added to the volatile hydrocarbon liquid fuel will vary, generally, upon a number of factors such as fuel volatility, local atmospheric conditions and the like. The precise de-icing amount can readily be determined at the refinery by quality control operations. Normally, from about 5 p.p.m. to about 500 p.p.m. of the reaction product of this invention will satisfactorily prevent carburetor icing. A preferred range of the de-icing composition of this invention is from about 10 p.p.m. to about 100 p.p.m.

In order to demonstrate the utility of the invention, the following examples are presented.

EXAMPLES

The following tests were conducted to determine the efficacy of the compositions of the invention as carburetor de-icers. The following describes the test apparatus and methods employed in performing these tests:

TEST EQUIPMENT

Engine

1965 production, Falcon engine, equipped with factory radiator, manifold, carburetor and automatic choke.

The following parts were removed or disconnected for reproducibility purposes: Air cleaner, radiator fan, thermostat and fast idle linkage, choke to throttle.

Test cell

A 160 cubic foot capacity, refrigerated by CO_2 -cooled Savasol with automatic temperature control and manually controlled humidity which was equipped with remote engine controls.

DETAILED TEST PROCEDURE

Test preparation

Prior to starting the test, the following was performed:

- (1) Drain engine fuel lines and carburetor.
- (2) Check thermocouple performance.
- (3) Stabilize temperatures as follows:

° F.

- (a) Underhood (air) ----- 36 ± 2
- (b) Oil sump ----- 36 ± 4
- (c) Water jacket ----- 36 ± 4
- (d) Carburetor air ----- 36 ± 2

- (4) Establish 100% humidity.
- (5) Remove fuel from cold storage and connect to fuel system.
- (6) Start engine.

5

Test period

- (1) Accelerate to 1500 r.p.m., no load.
  - (2) Maintain 1500 r.p.m. for one minute.
  - (3) Reduce speed to idle. Allow 30 seconds idle time.
- If engine does not stall, repeat steps (1) through (3). During the 30 second period, note engine "bucking" which would be indicative of ice formation, but without stalling. If engine stalls, record as such and restart engine immediately, repeating steps (1) through (3). Record idle time in seconds before stall occurs.
- (d) Items (1) through (3) constitute one cycle. Repeat as many cycles as necessary until throttle plate temperature rises above freezing or until three cycles are completed without stalling indication.
- (5) During the course of conducting items (1), (2) and (3), record throttle blade temperatures at the start of idle and at stall time, or end of idle. Record other temperatures (air, water and oil) immediately after idle.

TEST VARIABLES

60 In brief, the operating conditions and procedures used for conducting the tests were as follows:

Conditions

- 35 to 40° intake air
- 100% humidity
- Continuous air circulation

Procedure

- (1) Start cold engine.
- (2) Accelerate to 1500 r.p.m. and maintain for one minute.
- (3) Decelerate to idle r.p.m. and maintain for one-half minute. Observe and record engine stalling characteristics.
- (4) If engine stalls, immediately restart and rerun the cycles described by items (1) through (3) above.

The engine, atmospheric conditions and operating procedure selected for these studies were each planned to emphasize icing conditions so that the reduction of ice formation indicated by an additive would be further reduced by several times under normal consumer conditions.

Except that the engine load and speed must be low, the selection of optimum speeds for carburetor icing tests was relatively flexible. In general, the throttle opening should be at a minimum adjustment for prolonged engine warm-up and for maximum throttle blade exposure to the moist air; and yet, the throttle must be sufficiently opened to cause adequate fuel flow through the carburetor's primary jets so that freezing temperatures will result from vaporization of the volatile gasoline.

Engine speed to attain these conditions was established at 1500 r.p.m. and although ice formation began on the throttle blade at this speed, the engine seldom, if ever, stalled until the speed was reduced to idle. When decelerating from 1500 r.p.m. to idle, the air crack between the throttle valve and throttle body began filling with ice, shutting off air into the manifold. Just prior to stalling, the air fuel ratio became excessively rich and occasionally caused the engine to "buck" before stalling.

At temperatures below 35° F., the moisture content of the air is generally too low for the rapid build-up of ice necessary for stalling, but the maximum air temperature for stalling is not so well established because of the influence of fuel volatility and carburetor design. Usually, standard procedure during carburetor icing tests is to maintain the air temperature at a constant level throughout the test, at perhaps 40° F. The temperature control technique used deviated from this standard procedure since, during exploratory studies, it was observed that some additive compositions were prone to cause irregular icing rates at different temperature levels.

After conducting preliminary studies at constant temperatures, it was decided to try simulating consumer conditions by starting with a minimum air temperature of 35° F. and then allow a gradual rise in air temperature to a maximum at which ice would no longer form. Although this latter procedure introduced the problem of maintaining a constant air temperature increase rate, it appeared to provide a more valid, reproducible testing technique and was thus adopted as the procedure for these tests.

Humidity was maintained at, or near, 100% through use of a finely atomized water spray on the test cell cooling coils. Air circulation over these coils was held at a constant rate by means of a forced air-recirculating system.

SUMMARY OF RESULTS

Icing tests were conducted using a variety of de-icing compositions. For control purposes, Run A was made in which no de-icing compositions were employed. Run B represents a conventional addition of 1% isopropanol (10,000 p.p.m.). In Run C, a commercial multi-purpose additive which is normally employed as a de-icing additive and which comprises a 1-alkanol, 2-alkyl imidazoline, was added at 15 p.p.m. and at 30 p.p.m. The de-icing compositions of this invention were then evaluated in a similar manner. The additive in Run D represents a de-icing composition formed from reacting phosphorous pentoxide, as P_4O_{10} , with 1-(2-hydroxyethyl)-2-heptadecenyl imidazoline followed by the addition of octanol in a mole ratio of 1:4:2. Similarly, the de-icing composition used in Run E was a reaction product formed from the P_4O_{10} and imidazoline materials in a ratio of 1:6.

To demonstrate the surprising effectiveness of the de-icing compositions of this invention which are prepared with the specific mole ratios set forth above, other compositions were prepared with a mole ratio outside of the ranges which represent the compounds of this invention. Specifically, the same starting material used in Run D were employed. Run F was made with a composition

having a mole ratio of 1:1:5 while the composition of Run G was prepared using a mole ratio of 1:2:4.

All of the de-icing compositions were evaluated according to the test procedure set forth above. The results of these tests are presented below in Table I.

TABLE I.—DE-ICING COMPOSITION EVALUATIONS

De-icer	Amount, p.p.m.	Number of stalls	Number of bucks
A		17	2
B	10,000	11	1
C	15	17	0
C	30	11	0
D	27	8	0
D	14	12	1
D	7	13	0
E	40	9	0
E	27	7	2
E	14	13	0
F	40	16	2
G	40	16	0

As can be seen from the results presented above, the de-icing compositions of this invention are surprisingly effective in reducing the number of stalls under conditions which are most favorable for inducing icing difficulties in the operation of internal combustion engines. The de-icing compositions of this invention, Additives D and E, exhibit superior de-icing properties at surprisingly low dosage. In contrast, compositions resulting from starting with the same reactants in ratios other than those which fall within the practice of this invention (F and G) show substantially no improvement or advantage over a blank run involving no additive at all.

In addition to the compositions described above, various organic and inorganic salts thereof have also been seen to be equally effective as de-icing additives according to the process of this invention. Accordingly, it is contemplated that these materials fall within the spirit of this invention.

Having thus described the invention, what is claimed is:

1. A hydrocarbon motor fuel composition for preventing icing during operation of internal combustion engines consisting of (I) a major amount of a hydrocarbon distillate in the gasoline distillation range and (II) 4-400 p.p.m. of an equimolar phosphorylated composition having the formulae:

where E is from the group consisting of:

(A) a 1-alkanol or alkylamino 2-substituted imidazoline radical represented by the structure:

where R is an aliphatic group of 1-22 carbon atoms in chain length, Y and Z are selected from the group consisting of hydrogen and lower aliphatic hydrocarbon groups of not more than 6 carbon atoms in chain length, R₁ is an alkylene radical of 1-6 carbon atoms, Q is either O or NH and n is an integer of 1-50, and

(B) a monohydric alcohol or an aliphatic primary amine having from 1 to 18 carbon atoms with the proviso that at least 3 occurrences of E are (A).

2. The composition of claim 1 where E is (A).

3. The composition of claim 1 where the alkanol group of said imidazoline is 2-hydroxyethyl.

4. The composition of claim 3 where the 2-substituted group of said imidazoline contains between 12 and 22 carbon atoms.

5. The composition of claim 4 where the 2-substituted group of said imidazoline contains from 15 to 17 carbon atoms in an aliphatic chain.
